UNITED STATES PATENT OFFICE.

CHARLES K. GILES, OF CHICAGO, ILLINOIS.

DESIGN FOR A WATCH-CHAIN.

SPECIFICATION forming part of Design No. 14,978, dated April 29, 1884.

Application filed September 13, 1883. Term of patent 7 years.

To all whom it may concern:

Be it known that I, CHARLES K. GILES, a citizen of the United States, residing at Chicago, in the county of Cook and State of Illinois, have invented and produced a new and original Design for Watch-Chains, which is set forth in the following specification, reference being had to the accompanying drawing, in which a perspective view is shown of a watch-chain made after my new design.

I will proceed to describe in detail the features of my present invention, and will then point out definitely in the claim the special improvement which I believe to be new and wish to protect by Letters Patent.

My object is to provide a watch-chain of such design as to be peculiarly appropriate for persons employed or connected with railways; and the main feature of my design is to make the body or main portion of the chain to imitate in appearance the bell-cord of a railway-train provided with couplings at the ends made to imitate in appearance the ordinary couplings of such railway bell-cord.

In the drawing the body of the chain is represented as composed of two sections, A and B, each of which is made of separate strands wound or twisted together so as to present an appearance of a railway bell-cord, or composed of a single strand of suitable size grooved spirally, so as to present the same appearance, the material being any substance suitable for the purpose. The section A is provided at each end with coupling-pieces a and a', which are made to imitate the form and appearance of the open couplings on railway bell-cords, as shown in the drawing, and the section B is provided with similar couplings, b b'. The two sections are joined by coupling

together the two pieces a' b' the same as a bell-cord coupling, and when these are connected the two sections have the appearance of two sections of railway bell-cord coupled together. The usual hook, C, for attachment to the watch, is coupled to the section B by one or more links, or in any other suitable way.

In further carrying out my object, I make a guard-bar, D, to imitate the form of a railway-spike, and this bar is attached to the section A of the chain by links connected to the coupling a, or in any other suitable way. This feature of the bar is additional to the main feature of the design, and the leading idea may be carried out still further by attaching charms to the bar representing articles or implements used by railway men. In the drawing I have shown such charms, E and F, made to represent a railway-lantern and conductor's punch, respectively, which are connected by links, in the usual way, to the guard-bar.

As stated above with reference to the body, the different parts of the chain may be made of any material suitable for the purpose.

Having thus described my design, what I claim as new, and desire to secure by Letters Patent, is—

The design for watch-chains herein shown and described, the same consisting of the body formed to represent a railway bell-cord, with couplings at each end formed to represent railway bell-cord couplings, and a guard-bar formed to represent a railway-spike, and connected to one of the bell-cord couplings, substantially as set forth.

CHARLES K. GILES.
